(57) **CLAIM**

The ornamental design for a beverage bottle as shown and described.

DESCRIPTION

FIG. 1 is a perspective view of a beverage bottle;

FIG. 2 is another perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and

FIG. 8 is a bottom view thereof.

FIG. 9 is a perspective view of a beverage bottle in another example of the design;

FIG. 10 is another perspective view thereof;

FIG. 11 is a front view thereof;

FIG. 12 is a back view thereof;

FIG. 13 is a left side view thereof;

FIG. 14 is a right side view thereof;

FIG. 15 is a top view thereof; and,

FIG. 16 is a bottom view thereof.

The broken lines in the drawings depict portions of the beverage bottle that form no part of the claimed design.

1 Claim, 14 Drawing Sheets
